REVERSIBLE HAIR TRIMMER

Warren M. Mansfield, Glendale, Calif., assignor, by mesne assignments, to Roy P. M. Davis, Los Angeles, Calif.

Application January 24, 1949, Serial No. 439

Term of patent 14 years

(Cl. D22—3)

To all whom it may concern:

Be it known that I, Warren M. Mansfield, a citizen of the United States, residing at Glendale, in the county of Los Angeles and State of California, have invented a new, original, and ornamental Design for a Reversible Hair Trimmer, of which the following is a specification, reference being had to the accompanying drawings, forming part thereof.

Fig. 1 is a plan view of a reversible hair trimmer showing my new design.

Fig. 2 is an edge view looking in the direction of the arrows on line 2—2 in Fig. 1.

Fig. 3 is a plan view of the opposite side of the trimmer as shown in Fig. 1.

Fig. 4 is an enlarged end view looking in the direction of the arrows on the line 4—4 of Fig. 1.

Fig. 5 is an enlarged sectional view on line 5—5 of Fig. 1 looking in the direction of the arrows.

I claim:

The ornamental design for a reversible hair trimmer, substantially as shown.

WARREN M. MANSFIELD.
